UNITED STATES PATENT OFFICE

2,525,758

GAS HOLDER

John W. Allen, Chicago, Ill., assignor to
Chicago Bridge & Iron Company

Application November 2, 1945, Serial No. 626,210

3 Claims. (Cl. 48—178)

1

This invention relates to a gas holder for the storage of gases under pressure.

Gas holders of the general type set out herein are designed to store gas at a substantially constant pressure and are constructed with a freely floating roof which rides on the gas and rises and falls as the quantity of gas within the holder is increased and decreased. I have invented an improved type of gas holder that employs a seal between the roof and the shell of the holder to prevent the escape of gases. This seal has its major portion supported by the edge of the roof when the roof is in its lowest position and supported by the shell when the roof is in its highest position. The intermediate portion of the seal is bowed upward by the pressure of the gas within the gas holder. The new gas holder also uses simple light-weight guide means to guide the roof during its travel and maintain the roof substantially level.

The invention will be described as related to the embodiment shown in the accompanying drawings. Of the drawings Fig. 1 is a plan view of the gas holder partially in section; Fig. 2 is a vertical section taken along line 2—2 of Fig. 1 with the roof in lowered position; Fig. 3 is a vertical section similar to Fig. 2 with the roof in raised position; Fig. 4 is a partial vertical section taken along line 2—2 of Fig. 1 with the roof in lowered position; and Fig. 5 is a view similar to Fig. 4 with the roof in raised position.

The gas holder illustrated in the accompanying drawings comprises a cylindrical shell 10, a cylindrical roof 11 positioned therein, three pairs of guide means 12 spaced around the edge of the roof and contacting the inner surface of the shell 10 and a flexible seal 13 extending between the edge of the roof 11 and the inner surface of the shell 10.

The guide means 12 includes three upwardly extending brackets 14 attached to the top edge of the roof and carrying wheels 15 in contact with the shell 10. These top brackets are made up of two parallel plates with the wheels carried between the plates, and the brackets are spaced around the roof to divide its circumference into three substantially equal portions. More top guide means may be provided if desired, but three is the minimum number that will give the roof its desired stability. The bottom portion of the roof is of slightly smaller diameter than the sides of the roof, in order to form a recessed portion 16 at the bottom edge of the roof. This recessed portion carries downwardly extending brackets 17, serving as bottom guide

2

means. Each bottom bracket 17 is made up of parallel plates carrying a wheel 18 at its lower end in contact with the shell. Each bottom bracket 17 is aligned beneath a top bracket 14 and thus provides two points of contact on the shell for each guide means. This serves to give rigidity to the roof and to keep it in substantially horizontal position at all times. The top brackets 14 extend slightly above the top of the roof, while the bottom brackets 17 extend below the roof a distance substantially equal to the thickness of the roof. The bottom brackets have a greater extension than the top brackets in order to provide space for positioning the seal 13.

The seal 13 is preferably a fabric impregnated with a gas impervious flexible material. The material may be a synthetic rubber such as neoprene. The seal is of annular shape extending from the edge of the roof to the shell. The inner edge of the seal is fastened to the bottom of the roof at the outer surface 19 defined by the recessed portion 16. The edge of the seal is held in place by a circular band 20 and bolts 21 passing through the bottom 19, seal 13, and band 20. The seal extends upwardly along the side of the roof. The outer edge of the seal is fastened within a rectangular outwardly extending horizontal groove 22 provided in the shell. This groove is closed off from the interior of the shell by means of a vertical backing plate. The outer edge of the seal is clamped to the bottom surface of the groove 22 by means of bolts 24 and a circular band 25. The bolts 24 pass through the band 25, the bottom flattened edge of the backing plate 23, the edge of the seal, and the bottom of the rectangular groove 22. The plate 23 provides support for the seal when the roof is in an elevated position. The two edges of the seal are substantially aligned horizontally when the roof is about midway in its path of travel from its lowest position to its highest position. When the roof is in its lowest position (Fig. 4) the major portion of the seal is supported by the outer surface of the roof. When the roof is in its highest position (Fig. 5) the major portion is supported by the shell. The unsupported intermediate portion of the seal is bowed upward by the pressure of gas within the gas holder.

At the top of the shell there is an inturned flange 26 serving as a wind girder and rain shield, and also as a stop to limit upward movement of the roof. Beneath each bottom bracket 17 there is located a vertical well 27 into which the bracket passes when the roof approaches its lowest position.

The roof may be weighted so that the gas may be stored under any desired pressure. As shown in the drawings, this weighting includes a bottom bed of sand 28 capped by a layer of concrete 29. The concrete is held in place by an inwardly projecting flange 30 attached to the inner surface of the roof. When the gas holder is 100 ft. in diameter and the roof is 97 ft. in diameter 1100 cu. yds. of sand and 150 cu. yds. of concrete will provide a gas storage pressure of approximately 3 lbs. per square inch.

Having described my invention as related to a typical embodiment of the same, it is my intention that the invention be not limited by the details of description unless otherwise specified, but rather be construed broadly within its spirit and scope as set out in the accompanying claims.

I claim:

1. A gas holder comprising a substantially cylindrical shell, a substantially cylindrical weather roof therein adapted to rise and fall with increasing and decreasing quantities of gas and to rest on the bottom of the gas holder in its lowermost position, a vertically upstanding cylindrical wall about the periphery of the roof, at least three pairs of guide members positioned around the edge of the roof and contacting the inner surface of the shell, with each guide member carrying a wheel to contact the shell and each pair of guide members being vertically aligned with one of the guide members of each pair spaced above the roof and with the other guide member of each pair being spaced below the roof, an annular seal of substantially gas impervious flexible material having its inner edge attached to the vertical peripheral surface of the roof and having its outer edge attached to the inner surface of the shell between the spaced wheels on each pair of guide members, said seal having its major portion contacting the cylindrical wall when the roof is in its lowest position and contacting the shell when the roof is in its highest position with the intermediate portion of the seal bowed upward by pressure of gas within the holder, stop means located at the top of the shell and arranged to be contacted by the top guide members to limit upward travel of the roof, vertical wells at the bottom of the gas holder so located that the bottom guide members pass thereinto when the roof approaches its lowest position, and means for introducing gas into the shell below the level of the attachment of the seal to the shell.

2. A gas holder comprising a substantially

cylindrical shell, a substantially cylindrical weather roof therein adapted to rise and fall with increasing and decreasing quantities of gas, and to rest on the bottom of the gas holder in its lowermost position, a vertically upstanding cylindrical wall about the periphery of the roof, at least three pairs of guide members positioned around the edge of the roof and contacting the inner surface of the shell, with each guide member carrying a wheel to contact the shell and each pair of guide members being vertically aligned with one of the guide members of each pair spaced above the roof and with the other guide member of each pair being spaced below the roof, an annular seal of substantially gas impervious flexible material having its inner edge attached to the vertical peripheral surface of the roof and having its outer edge attached to the inner surface of the shell between the spaced wheels on each pair of guide members, said seal having its major portion contacting the cylindrical wall when the roof is in its lowest position and contacting the shell when the roof is in its highest position with the intermediate portion of the seal bowed upward by pressure of gas within the holder, vertical wells at the bottom of the gas holder so located that the bottom guide members pass thereinto when the roof approaches its lowest position, and means for introducing gas into the shell below the level of attachment of the seal to the shell.

3. The gas holder of claim 2 in which the guide members beneath the roof are substantially completely inserted in said wells when the roof is in its lowermost position.

JOHN W. ALLEN.
